CROSS WINDING FRAME WITH CONTINUOUS YARN FEEDING

Wilhelm Esser, Gustav Kahlisch, and Walter Reiners, Gladbach-Rheydt, Germany; vested in the Alien Property Custodian

Application March 29, 1940, Serial No. 326,642
In Germany May 3, 1939

8 Claims. (Cl. 242—35.6)

In winding twisted or good yarns, which only occasionally give rise to yarn breaking, the yarns, supplied by cops accommodated in a multi-bobbin carrier, are knotted together in order to attain a continuous supply of the cop threads to be collected in a cross wound bobbin. Owing to the limited space existing in the supply bobbin magazine, the position of both yarn ends of the cops at the lower end of the tube, and the necessity of particularly clean knots in consideration of the jumping over of the continually unwinding thread from cop to cop, it has up to the present not been considered advisable to apply automatic knotting devices in cross winding frames of this type. Although in cross winding frames with circulating winding units the starting ends of the yarns from several supply bobbins have been laid ready for facilitating the automatic knotting of the starting end to the end of the yarn wound on the cross wound bobbin, it has never been proposed to automatically produce a single yarn which consequently can be fed continuously.

According to the invention an automatic knotting device is coordinated to each supply bobbin magazine so that the trailing ends and the starting ends of the yarns of consecutive supply bobbins placed ready for knotting are automatically knotted together when passing through the range of their knotting device, the knotting device being preferably controllable from the circulating magazine, in cross winding frames having a plate magazine. If the magazine circulates continuously its speed must be such that the distance through which a reserve bobbin has to travel up to the feeding position corresponds to the yarn length of a cop, this ensuring a continual feeding, with preliminarily sorted cops.

The invention further provides means which cause the yarn to jump from cop to cop always at the moment, at which the bobbin in the running position is exhausted, in that to this bobbin a feeler is co-ordinated which, when the bobbin is exhausted, engages the drive for the movement of the magazine. It is hereby attained that a predetermined number of cops can be wound on every cross wound bobbin. In order that nevertheless winding bobbins, or cross wound bobbins of predetermined maximum diameter are obtained also in this instance, an arrangement is provided which, when the maximum diameter of the bobbin is attained, automatically exchanges this bobbin for an empty tube and brings other empty tubes into position ready

for use, so that the operation in the winding bobbin head also progresses uninterruptedly.

As in an average half shift approximately four cross wound bobbins are produced, it is sufficient for half a shift to mount the empty tubes in a revolving device, which might take up any further number of empty tubes without departing from the usual construction of the cross winding frame, if it is not fed from a magazine, as is also provided according to the invention.

An embodiment of the invention is illustrated by way of example in the accompanying drawings, in which:

Fig. 1 shows in side elevation partly in section two opposite winding units of the same winding frame,

Fig. 2 is a top plan view of a supply bobbin head,

Fig. 3 is a plan view of two winding units according to Fig. 1 as seen from the front.

The winding frame is composed in known manner of transverse frames for accommodating the winding heads, and the supports and shafts common to all heads. In the example illustrated, a common drive is provided for the shafts 1, 2, 3, 4, 5, 6, 7; the shafts 1 and 3 to 7 being revolved continually. There are further provided conveying bands 11 and 12, with collecting gutters 13 and 14, which move through all winding points.

There is a supply bobbin magazine for each winding point, each magazine comprising a revoluble plate 21 having inclined pins 22 (four in this case) to receive the tubes H of supply bobbins K. The plate 21 is mounted on a shaft 26 journalled in bearings 26a, 26b in the casing of a gear box 26c, and may be detachably secured to the shaft, if the bobbins are to be pegged on a dismounted plate; or fixed to the shaft, if the bobbins are to be pegged with the plate in the machine. As seen in Fig. 2, the bobbin K₁ is in running position, the bobbin K₂ is in reserve position, and the bobbins K₃ and K₄ are in loading position. The direction of rotation of the plate is indicated by the arrow A. The plate 21 has a slot 23 and a clamp 24 for each adjacent pair of pins 22. Each slot and its appurtenant clamp constitute a yarn end holder, in which the trailing end of the yarn on one bobbin can be laid side by side with the leading end of the yarn of the next following bobbin. Between the slot and the clamp is thus stretched a free span of yarn ends ready to be engaged by a knitter, in a manner to be described. Above the plate 21 and behind the

running bobbin K_1 is a stripper 25 for empty tubes, from which stripper the tubes H drop into the receiver formed by the conveyor band 11 and gutter 13. The shaft 26 is intermittently driven from shaft 3 by worm-wheels 27, 28, each time a clutch 20, shown in Fig. 2, is released for engagement by a relay 30, 31. The relay is controlled by a switch 32a operated by a feeler 32 bearing against the last yarn windings of the running cop K_1 . The armature 30 of the relay is urged against the influence of the electromagnet 31 by a spring 30a; consequently the arrival of the reserve bobbin K_2 in the running position causes the disengagement of clutch 20 by opening switch 32a. The knotting device 45 may be of any suitable construction and will therefore not be described in detail. It is supported upon a post 44 rockably mounted on shaft 1. The post 44 has a lateral arm 43 carrying a roller 42, which bears against a cam disk 41 under the pull of a spring 44a. The cam disk 41 is fixed to shaft 26 and so rotates with the magazine plate 21. The knotting device 45, it will be observed, is positioned so as to engage the free span of yarn ends stretched between the slot 23 and clamp 24 located between the reserve bobbin K_2 and the next following bobbin, K_3 , which is in one of the loading positions. The knotting device is of the type which is operated by rotation of a bush 46 freely mounted on a shaft 46a. The bush 46 has a sliding bolt 46b urged by a spring 46c to engage in a socket 48a of a sprocket wheel 48 fixed to shaft 46a. The sliding bolt 46b is normally restrained by a dog 50 pivoted at 50a on the casing of the knotting device. The dog is moved to release the sliding bolt 46b by the engagement of its tail 51 with a stop 52 pivoted at 52a on the frame of the machine and held against rocking in one direction by a finger 52b. The sprocket wheel 48 is connected by a chain 49 to a sprocket wheel 47 fixed to shaft 1, and is thus continuously rotated.

At every part rotation of plate 21 and cam disc 41 the knotting device 45 is temporarily rocked in outward direction, while the yarn ends ready in clamp 24 come into the range of the knotting elements of the knotting device 45, which then rocks inwards and makes a knot. Thus the trailing yarn end of the reserve cop is connected with the starting yarn end of the cop which will move into the reserve position after it.

The head for the winding bobbins may be of any desired construction. The guiding of the running-on threads F and the drive of the winding bobbins S are performed, in the example shown, by driving drums 61 acting as cam cylinders or slit-drums. Holders for the tubes L of the winding bobbins S are mounted on the free end of oscillatable yokes 62, which swing about bearing bushes 63 of a shaft 64. For simplifying the replacing of the tubes revolving cages are provided, in the example illustrated, adapted to hold a number of empty tubes. Each cage comprises a hub 66 fixed upon a shaft 65 journalled in the free ends of the corresponding oscillatable yoke 62, the hub having at its two ends radial arms 67 and 68 forming crosses to support the tubes. The arms 67 of one of the crosses carry stationary gripper elements of the holders for the empty tubes L , while the arms 68 of the other cross carry gripper elements 69-70 which are adapted to swing outwards. The latter are equipped with a control lug 71 and held in closed position by a spring 72, ex-

cept when the lug 71, during the rotary movement of the revolving cage, runs up on a curved bar 73 adjustably fixed on frame 62, and is swung into the open position.

The revolving cage 66, 67, 68 is intermittently fed, according to its subdivision (for four tubes in this case), by a sprocket wheel 74 and a chain 75, as soon as the flange of a bush 77 carrying a sprocket wheel 76, which is mounted to revolve freely upon shaft 64, is coupled with a toothed wheel 84 driven from shaft 6 by means of a toothed wheel 85. This coupling is effected by a sliding bolt 77a on bush 77 urged by a spring 77b toward a socket 84a of gear 84. The sliding bolt is normally restrained by an arm 83 fixed to a shaft 82, which also has fixed to it an arm 81 bearing upon the top of one of the arms of the yoke 62. The arm 81 is rocked by the yoke arm 62 and releases the coupling when the full diameter of bobbin S has been attained. The control arm 81 is further linked by a rod 91 with a double lever 92, 93, the free end of said double lever being influenced by an eccentric 94 adjustably fixed on a worm 95 and loosely rotating with this worm on the shaft 2, as soon as a worm wheel 96 keyed on shaft 26 rotates. The eccentric 94 is exchangeable and of such shape that, after a predetermined number of part rotations of plate 21 and shaft 26, the rod 91 is lifted far enough to release the locking lever 83 from the coupling bolt 77a, which clutches the bush 77 to the toothed wheel 84.

Besides the sprocket wheel 76 a control disc 98 is mounted on bush 77, as shown in Fig. 3, and acts upon a control bolt 99 of a rod 108, one end of said rod being curved to form a hair-pin guide sliding on the bush 77 and the other end acting upon a bell-crank lever 101, 102. This bell-crank lever 101, 102 carries a cutting element, shown by way of example as a serrated knife 103 or as a straight cutting edge 104. Also a guide plate 105 is fixed on the arm 102 of the bell-crank lever.

To each revolving cage a magazine 106 for empty tubes, open at both ends, is coordinated, the tubes L being prevented from slipping out by a hinged bottom plate 107, serving as an escapement. The curved bar 73 may be adjusted on the yoke 62 and the magazine 106 on its carrier 108 so that the uppermost tube holders of the revolving cage, when the desired bobbin diameter has been attained, are at the ends of the lowermost tube L in the magazine 106, when the revolving cage begins to turn. Then, when the revolving continues, the tube holder closes and clamps the tube, as the projection 71 slips off the curved bar 73. The tube is thus carried along, the bottom plate 107 yielding temporarily as the tube leaves the magazine.

The cross winding frame as described operates in the following manner: It is assumed that four supply bobbins K are skewered on the magazine table 21 and that the yarn has been threaded through tensioner T and the slot of driving drum 61 to the lower tube L on the winding bobbin holder; also, that the shafts 1 and 3-7 are rotating and the tube L is therefore being driven by the drum 61 and the yarn winding upon it. The leading ends of the bobbins K_3 and K_2 are knotted respectively to the trailing ends of the bobbins K_2 and K_1 . The leading end of the bobbin K_4 and the trailing end of the bobbin K_3 are placed in the corresponding slot and clamp 24. When the bobbin

K_1 is exhausted, the thread jumps across to the bobbin K_2 and the winding proceeds. At the same time the feeler 32 is rocked by its spring and closes the switch $32a$. This excites the electromagnet 31 and the armature 30 moves in the direction of the arrow, engaging the clutch 20 . The shaft 26 begins to rotate, moving the peg of bobbin K_1 through the stripper 25 and stripping off the tube H of this bobbin, which falls onto the conveyor 11 . The reserve bobbin K_2 , meanwhile, moves toward the running position and the bobbins K_3 and K_4 advance accordingly. When the plate 21 has completed a quarter revolution the bobbin K_2 has moved against the feeler 32 and opened the switch $32a$, disengaging the clutch 20 and stopping the rotation of shaft 26 .

Meanwhile, the cam disk 41 has executed a quarter revolution, during which the arm 43 has rocked the post 44 and the knotting device 45 mounted on it to the right, until the position shown in dash lines in Fig. 1 is reached. During this movement, the tail 51 of dog 50 rocks the stop 52 to the right and passes under it. Thereupon the roller 42 drops off the high part of the cam 41 and the knotting device rocks toward the left, into engagement with the yarn ends of bobbins K_2 and K_4 , which at this moment have arrived in the position occupied by the yarn ends of bobbins K_2 and K_3 in Fig. 2. As the knotter rocks to the left the tail 51 of dog 50 strikes the stop 52 and the dog is lifted out of engagement with the sliding bolt $46b$, which is thrust into the socket $48a$ of sprocket 48 by its spring $46c$. The bush 46 of the knotter is thereby turned through one revolution, which is sufficient to cause the knotter bills to complete the knot. At the close of the revolution of the knotter bills the dog 50 , which has resumed its original position, cams the sliding bolt $46b$ out of the socket $46a$ and stops the knotter. The magazine is now in the same condition as at the start, except that the bobbins have moved up one step and one of the pegs 22 is ready to receive a new bobbin. The mounting of new bobbins on the pegs can be allowed to await the arrival of the first empty peg in the position of the bobbin K_3 in Fig. 2. In mounting the bobbin on the peg the operative brings together the trailing end of the preceding bobbin with the leading end of the bobbin just mounted and places them in the intermediate slot 23 and clamp 24 .

The bobbin S continues to accumulate yarn until, a predetermined number of cops K having been unwound, the cam 94 has released lever 92 , 93 and arm 81 has been raised by the link 91 to withdraw the end of the arm 83 from the coupling bolt $71a$. When this occurs, the coupling bolt engages the socket $84a$ of gear 84 and the bush 77 begins to rotate. Through the chain and sprocket connection 74 , 75 , 76 , the bobbin cage begins to revolve. At the first movement of the bobbin cage the lug 71 of the upwardly directed tube gripper 69 , 70 moves off the cam 73 and the spring 72 throws the gripper against the tube end, the grippers 67 and 70 being at this moment positioned exactly at the ends of the bottom tube in the magazine 106 . Upon further movement of the revolving cage the gripped tube is pulled out of the magazine, flap 107 yielding to permit its escape and then closing to catch the next tube above. The rotation of the revolving cage moves the full bobbin S upward, while the knife 103 , or 104 , actuated by

the cam 98 and link 100 , moves toward the position shown in dash lines at the right side of Fig. 1. When the revolving cage has moved through approximately a quarter revolution, the lug 71 of the gripper holding the completed bobbin, cammed over by cam 73 , has opened the gripper to the point where the bobbin can escape and roll down the guide 105 to the trough 14 and thence to the conveyor 12 . The trailing yarn from the wound bobbin is caught by the knife 103 , or 104 , and severed, but is first brought against the new tube L which has been moved into running position by the quarter revolution of the revolving cage. If the yarn is stiff or smooth, the empty tube will be coated locally or completely, with adhesive, in order to catch the yarn and start the winding of the new bobbin.

If the winding bobbin S should reach a maximum diameter before the predetermined number of supply cops has been unwound, the arm 81 would be raised by the yoke 62 to the point where the end of arm 83 would be withdrawn from the coupling bolt $71a$ and the change of winding bobbins so initiated.

If the tube holders are not in a revolving device, but, as usual, on the front ends of frame 62 , a corresponding locking device and so forth must be provided, which prevents an empty tube from sliding out before the holder of the completed cross wound bobbin is liberated, or a feeding device which moves the magazine with its lowermost tube between the opened holder and lifts it again after the tube holder has been closed.

What we claim as our invention and desire to secure by Letters Patent of the United States is:

1. In a cross winding frame, winding means, a cyclically movable supply magazine therefor, comprising supports for a plurality of supply bobbins adapted to travel, as the magazine moves, through a loading position, a reserve position, and a running position; means on said magazine for holding, side by side in a free span, yarn ends of bobbins on neighboring supports of said magazine; and knotter means located near said magazine in position to engage the free span of yarn ends of two adjacent bobbins.

2. In a cross winding frame, winding means, a cyclically movable supply magazine therefor, comprising supports for a plurality of supply bobbins adapted to travel, as the magazine moves, through a loading position, a reserve position, and a running position; means on said magazine for holding, side by side in a free span, yarn ends of bobbins on neighboring supports of said magazine; knotter means located near said magazine in position to engage the free span of yarn ends of two adjacent bobbins; driving means for said knotter means; and starting means for controlling the operation of said knotter means by said driving means, including an element movable in conjunction with said magazine.

3. In a cross winding frame, winding means, a cyclically movable supply magazine therefor, comprising supports for a plurality of supply bobbins adapted to travel, as the magazine moves, through a loading position, a reserve position, and a running position; means on said magazine for holding, side by side in a free span, yarn ends of bobbins on neighboring supports of said magazine; knotter means located near said magazine in position to engage the free span of yarn ends of two adjacent bobbins; and

means for intermittently moving said magazine, comprising driving means and control means, said control means including a feeler adapted to engage the bobbin in running position to detect the exhaustion of yarn therefrom.

4. In a cross winding frame, winding means comprising means for supporting a tube for rotation, means for rotating the tube, and means for releasing the tube from said support; a cyclically movable supply magazine for said winding means, comprising supports for a plurality of supply bobbins adapted to travel, as the magazine moves, through a loading position, a reserve position, and a running position; means on said magazine for holding, side by side in a free span, yarn ends of bobbins on neighboring supports of said magazine, knotter means located near said magazine in position to engage the free span of yarn ends of two adjacent bobbins; and means movable progressively by said magazine to operate said tube releasing means at the end of a predetermined extent of movement of said magazine.

5. In a cross winding frame, winding means comprising means for supporting a tube for rotation, means for rotating the tube, and means for releasing the tube from said support, said last means being responsive to an element movable progressively as the winding proceeds; a cyclically movable supply magazine for said winding means, comprising supports for a plurality of supply bobbins adapted to travel, as the magazine moves, through a loading position, a reserve position, and a running position; means on said magazine for holding, side by side in a free span, yarn ends of bobbins on neighboring supports of said magazine; and knotter means located near said magazine in position to engage the free span of yarn ends of two adjacent bobbins.

6. In a cross winding frame, winding means comprising means for supporting a tube for rotation, means for rotating the tube, means for releasing the tube from said support, and means for supplying a new tube to said support; a cyclically movable supply magazine for said winding means, comprising supports for a plurality of supply bobbins adapted to travel, as

the magazine moves, through a loading position, a reserve position, and a running position; means on said magazine for holding, side by side in a free span, yarn ends of bobbins on neighboring supports of said magazine; and knotter means located near said magazine in position to engage the free span of yarn ends of two adjacent bobbins.

7. A cross winding frame as described in claim 6, wherein said means for supporting a tube for rotation comprises a cage having a plurality of tube engaging devices, and a rocking yoke on which said cage is revolubly mounted; said means for supplying a new tube to said support comprising a tube magazine having escapement means adapted to release tubes therefrom one at a time, said cage being adapted to move as the winding progresses, to bring a discharged tube engaging device thereof into position to grasp the tube at the escapement of said tube magazine, and means for causing said engaging device to grasp said tube upon reaching said position.

8. In a cross winding frame, winding means comprising a driving drum, a rocking yoke, a cage revolubly mounted on said rocking yoke, said cage having a plurality of tube engaging devices movable by revolution of said cage to bring their respective tubes into engagement with said driving drum to be rotated thereby, means for supplying new tubes to said tube engaging devices when they reach a certain position, a supply magazine adapted to bring supply bobbins successively into position for running yarn onto the active tube of said winding means, yarn severing means comprising a cutter mounted to swing between the winding package and said driving drum, and control means whereby a cutting movement of said yarn severing means is coordinated with a movement of said cage to bring a new tube into engagement with said driving drum, said yarn severing means being adapted to move the supply end of the yarn against said new tube.
